ATTORNEYS

UNITED STATES PATENT OFFICE.

FRIEDRICH ADOLF RICHTER, OF RUDOLSTADT, GERMANY.

MUSICAL INSTRUMENT.

SPECIFICATION forming part of Letters Patent No. 519,737, dated May 15, 1894.

Application filed November 16, 1893. Serial No. 491,143. (No model.)

To all whom it may concern:

Be it known that I, FRIEDRICH ADOLF RICHTER, a subject of the King of Bavaria, residing at Rudolstadt, a city of the principality of Schwarzburg-Rudolstadt, Germany, have invented certain new and useful Improvements in Musical Instruments, of which the following is a specification.

My invention relates to reed valves for automatic musical instruments, and has for its object to improve and simplify the construction of reed valves employed in the above described class of instruments. I attain this object by means of the mechanism illustrated

15 in the accompanying drawings, in which—

Figure 1 is an elevation partly in section of a form of reed valve hitherto in use. Figs. 2 and 4 are views showing reed valves mounted on a reed-box and having my improvement 20 applied thereto. Fig. 3 is an elevation of a modification. Fig. 5 is a detail view of my improved reed valve. Fig. 6 is a detail view of the guide-plate so called. Figs. 7 and 8 are details hereinafter referred to.

25 The opening and closing of reed valves for automatic musical instruments has hitherto been accomplished, as shown in Fig. 1, by causing the points of the pivoted lever *y* supported by a suitable pivot *x* and connected to 30 the reed valves *d*, by wire 2, to be moved up and down by a perforated note-plate or a note-plate provided with elevations which is moved over said points.

It will be understood that the reed valve is 35 moved by a spring, which, when the lever *y* is in its normal position, will be under tension, and will serve to open the reed valve when the lever *y* is allowed to move from its normal position by entering a perforation in 40 the note-plate, or riding over an elevation, when the note-plate is provided with elevations.

According to my invention I actuate the reed valves by means of levers *f* having points 45 *a*, which levers are preferably made of one piece and rest directly and are supported upon the spring tongue *b* of the reed valve *d*, (preferably having points *f'* which pass through apertures in the spring tongue *b*,) 50 the reed valve *d* being held under tension by

a spring *c* made integral with the spring tongue *b*. My preferred method of forming the springs for the reed valve *d* is to stamp out and bend up a tongue as *b* from a plate *d'* having also integral therewith the spring *c*. 55 The reed valves cover suitable valve seats in the reed-box *g* in which are located the reeds *e*. The points *a* of the levers *f* project through apertures *k'* in the guide-plate *k*. Over these projecting points passes a note-plate *m* having perforations *m'* of varying lengths, or else provided with elevations (not shown).

The operation of the device is as follows: The normal position of the levers and reed valves is shown in Fig. 4, wherein the point 60 *a* projecting through the aperture *k'* rests against the traveling note-plate *m* and holds the reed valve firmly against the reed-box and the spring *c* under tension. As soon as an aperture in the note-plate comes opposite the point of the lever, the tension of the spring 65 *c* forces the point *a* through the perforation in the note-plate, raising the reed valve *d* and holding it open during the time that the aperture *m'* is opposite the point *a*. This is the 70 position of playing, and is shown clearly in Figs. 2 and 3. As a note-plate *m* continues to move, the edge of the perforation *m'* will press against the inclined face of the point *a* and force it down, at the same time moving the 75 lever *f* and closing the reed valve *d*.

I may employ points *a* having a variety of surfaces, two of which are shown in Figs. 7 and 8, in order to accomplish the closing of the reed valve *d* by a suitable cam action between the point *a* and the edges of the perforations *m'* in the note-plate. 85

I do not herein limit myself to the precise devices shown, as the device may be greatly varied by any skilled mechanic, without departing from the spirit of my invention. 90

What I claim, and desire to secure by Letters Patent, is—

1. In an automatic musical instrument, the combination of a reed-valve *d*, a spring *c* for 95 supporting the same under tension, a tongue *b* integral with the spring *c* and bent up at an angle to the reed valve, a lever *f* having one end bearing directly upon the tongue *b* and supported thereby and having its free 100

end projecting into the path of a note plate and operated thereby substantially as described.

2. In an automatic musical instrument, a reed valve having a spring, and a spring tongue stamped out of the same piece of metal as the spring, and bent up to form a bearing for an operating lever, substantially as described.

In testimony whereof I have signed my name to this specification in the presence of ~~10~~ two subscribing witnesses.

FRIEDRICH ADOLF RICHTER.
